UNITED STATES PATENT OFFICE.

FRANCIS M. CASE, OF CLEVELAND, OHIO, ASSIGNOR TO THE HOOVER SUCTION SWEeper COMPANY, OF NEW BERLIN, OHIO, A CORPORATION OF OHIO.

SUCTION SWEeper.

1,408,074.

Specification of Letters Patent. Patented Feb. 28, 1922.

Application filed March 8, 1917, Serial No. 153,437. Renewed March 20, 1918. Serial No. 223,674.

To all whom it may concern:

Be it known that I, FRANCIS M. CASE, a citizen of the United States, residing at Cleveland, in the county of Cuyahoga and State of Ohio, have invented a certain new and useful Improvement in Suction Sweepers, of which the following is a specification.

My invention relates to a suction sweeper and particularly to the means for adjustably and removably mounting the brush. It is illustrated in the accompanying drawings, wherein—

Figure 1 is an end elevation;

Figure 2 is a section along the line 2—2 of Figure 1;

Figure 3 is a section along the line 3—3 of Figure 2;

Figure 4 is a detailed elevation.

Like parts are indicated by the same letter in all the figures.

A is a housing connected by any suitable means not here illustrated with a suction means such as is common in connection with suction sweepers. One side of this housing is open as at A¹ to furnish a suction nozzle through which the air may be drawn and within which the brush may rotate by any suitable means not here shown, to clean a carpet or other covering by vibration, by brushing and by suction. The suction nozzle A¹ is bounded on both sides by flanges A² A³ which furnish a bearing surface for the carpet as it is drawn up by the suction against the nozzle slightly wider than the width of the housing wall for the purpose of preventing too great friction between the carpet and the edges of the nozzle. Extending across the suction nozzle are a series of fingers A⁴ A⁵. There may be a plurality of these fingers and depending on the length of the nozzle there may be any number sufficient to furnish an adequate support to position the carpet in the path of the brush and to prevent its being drawn clear into the nozzle and caught up or wound about the brush. These fingers are arranged in pairs being joined by the lateral member A⁵ so as to form a substantially U-shaped structure which penetrates the wall of the housing

through apertures A⁶. A⁷ is a countersunk aperture adapted to be engaged by a screw A⁸ engaging the wall to hold the spring fin-

gers in position. It will be noted that these fingers are slightly curved in front of the brush and terminate near one side of the nozzle just short of its wall. They may be removed by releasing the screw and withdrawing the U-shaped structure, however, under ordinary circumstances in view of the construction which I am about to describe in connection with the brush, it will not be necessary to remove them.

The ends of the housing are provided with relatively large circular apertures as indicated, such apertures being provided with a wall B and closed by a plug B¹ centrally countersunk as at B² to engage the curved lug B³ on the spring finger B⁴ which spring finger is provided at one end with handle flanges B⁵ and is rotatably mounted on a screw B⁶ on the housing so that by moving the finger to one side the spring will yield sufficiently to permit the lug to be released from the countersunk center and the spring finger may then be moved aside to permit the plug to be withdrawn.

C is a brush shaft. C¹ is a bearing sleeve, there being one at either end of the shaft. C² is a brush rotatably mounted on the shaft, the bearing sleeve C¹ extending slightly beyond the end of the brush. C³ is an adjusting and supporting collar. The shaft is squared as at C⁴ to engage the socket in the collar whereby it is held against rotation. This collar, it will be noted, is provided with a hub C⁵ in contact with the sleeve C¹ and is channeled as at C⁶ about such hub, the flange C⁷ forming said channel being adapted to surround and extend outwardly a short distance beyond the end of the brush so that the end of the brush is covered by such flange, the brush and flange being out of contact.

The collar C³ is provided at two points diametrically opposed with outwardly extending narrow lugs or ears D projecting upwardly from but integral with wider lug members D¹. These wider lug members D¹ are adapted to rest upon the plug B¹. They are provided on either side with a T-shaped air passage D². This T-shaped air passage D² is bent toward the plug B¹. D³ D⁴ are air passages extending through the collar from the air passage D² dis-

charging into the channel C⁶. D⁴ D⁴ are pins extending inwardly from the lug members D through the passages D² adapted to penetrate one or the other of the 5 perforations D⁵, D⁶, D⁷, D⁸, D⁹, D¹⁰ which extend clear through the plug B¹. The purpose of the reinforcing lugs D is merely to stiffen the structure and prevent all possibility of the pins breaking out. It will be 10 understood that the pins pass right through the T-shaped air passage and the air may circulate around them.

The distance between the centers of the holes D⁶, D⁶ equals the distance between the 15 pins D⁴ D⁴. This distance is equal to the distance between the holes D⁶ D⁷, the distance between the holes D⁷ D⁸, the distance between the holes D⁸ D⁹, the distance between the holes D⁹ D¹⁰, so that the pins D⁴ 20 may engage any adjacent pair of these holes but cannot, as for instance, engage holes D⁶ D⁹ at the same time.

It will be evident that while I have shown 25 in my drawings an operative device still many changes might be made both in size, shape and arrangement of parts without departing materially from the spirit of my invention.

It will be noted that the part A⁵ is contained 30 within the slot A⁹ being clamped into position by a screw, the inclined head of which jams the part A⁵ into the slot.

The use and operation of my invention are 35 as follows:

Assuming that the parts are in position as indicated in Figure 1, and that it is necessary for any reason to remove the brush, and particularly that it is necessary to adjust it vertically, we proceed as follows:—

The spring finger which secures the end 40 plate in position may be lifted so as to be freed from the central recess in the plate and swung round to one side so as to leave the plate unsupported. The plate can now be 45 pushed out, whereupon the end of the brush will be free. The brush can now be withdrawn endwise for any desired purpose. If the brush is driven by a belt, the pulley would ordinarily be approximately in the 50 middle of the brush, and by inserting the hand through the nozzle or opening in the mouth of that portion of the case here shown the belt can be thrown off of the pulley and the brush be removed.

If it is necessary to adjust the brush it 55 can be done by inserting the pins in the appropriate corresponding holes in the plates at each end, the removed plate being restored to position for that purpose. This 60 is possible because the distances from the upper hole on one side to the two upper holes on the opposite side are equal. There may of course be more holes than here shown, but in this case there would be five several positions of adjustment, and these ought to be 65

sufficient to take care of the ordinary wear of the brush, or to adapt it for use with the various kinds of carpets, rugs or floor coverings with which it is intended to be used.

The fingers or guards which lie beneath 70 the brush and across the nozzle or opening are preferably secured in the manner indicated so as to be permanently in position. This is of course possible when the brush is to be removed endwise, but would not be possible 75 if the brush were required to be removed outwardly through the nozzle opening. The three special features of the structure here shown are the permanent finger guards, the end removal of the brush and the 80 vertical adjustability of the brush, but I do not wish to be understood as limiting myself to the particular proportions, details and forms of construction by which these several results are accomplished.

By the expression "brush mounting means" we wish to be understood as referring to whatever device may be interposed between the brush and the casing to support the brush as distinguished from the 85 casing itself upon which the brush is, of course, mounted and which therefore in one sense of the word might be called the brush mounting means. It is obvious that either the pins or the holes may be arranged in 90 groups or series or sets and it is also obvious that if the holes are arranged in sets the pins need not be and if the pins are arranged in sets the holes need not be. It is also obvious that in the structure shown the 95 pins and holes must be placed on opposite sides of the axis of the brush, though, of course, other arrangement of pins and holes could be made without departing from the 100 spirit of this invention.

Another feature of the invention here disclosed is the use of the holes in the end of the case or in the adjusting plate in the end of the case for leading in air to be used in combination with the other parts as a thread 110 or dust guard for the end of the brush. For this purpose, of course, the end portion of the case need not be removable for the pins, of course, could be introduced from outside 115 through the holes in the apertures in the brush guard device or parts associated with the end of the brush. By the arrangement here shown and thus described one or more of these holes will always be open and since the channels in the end of the case lead to the channel about the end of the brush air will be drawn through the hole in whatever position of the adjustment the parts may be when the machine is in operation and this current of air drawn inwardly about the end 120 or flanged around the brush will protect its bearing and associated parts.

I claim:

1. In a suction cleaner the combination of 125 a casing provided with a dust inlet with a 130

- brush mounted near such inlet and brush mounting means between the casing and the brush, said casing and brush mounting means being provided one of them with pins and the other with holes, said holes arranged in two groups on opposite sides of the brush axis. 65
2. In a suction cleaner the combination of a casing provided with a dust inlet with a brush mounted near such inlet and brush mounting means between the casing and the brush, said casing and brush mounting means being provided one of them with pins and the other with holes, said holes arranged in two groups on opposite sides of the brush axis, said holes arranged so that certain ones in each group are equi-distant from a certain two adjacent ones in the opposite group. 70
3. In a suction cleaner the combination of a casing having a dust inlet and an end aperture with a removable closure, with a brush mounted near the inlet and brush mounting means between the closure and the brush, said closure and brush mounting means being provided one of them with pins and the other with a group of holes arranged at one side of the axis of the brush and adapted to successively receive one of the pins. 75
4. In a suction cleaner the combination of a casing having a dust inlet and an end aperture with a removable closure, with a brush mounted near the inlet and brush mounting means between the closure and the brush, said closure and brush mounting means being provided one of them with pins and the other with holes, said holes arranged in two groups on opposite sides of the brush axis. 80
5. In a suction cleaner the combination of a casing provided with a dust inlet with a brush mounted in such inlet and brush mounting means between the casing and brush, said casing and brush mounting means being provided with two sets of co-operating elements, each set consisting of two differing but cooperating species of elements, one of such species being arranged in a group at each side of the axis of the brush and adapted to selectively engage one element of the other species. 85
6. In a suction cleaner an open suction nozzle, a brush mounted for rotation therein, the nozzle being permanently open for the inward passage of air and dirt, the end walls of the nozzle being apertured, removable closures for such apertures and adjustable bearing supports for the brush mounted on said closures, the bearing supports being immovable when the closures are in the aperture closing position. 90
7. In a suction cleaner a casing having an air inlet in the bottom and openings in its ends, in combination with a brush and brush support therefor, said brush support provided with air passages leading from the end openings past the ends of the brush and pins adapted to be received in certain of said end openings and brush support so as to support the brush on the casing and leave at all times an air passage from the end openings through the support and past the ends of the brush. 95
8. In a suction cleaner an open suction nozzle, a brush mounted for rotation therein, the nozzle being permanently open for the inward passage of air and dirt, the end walls of the nozzle being apertured, removable closures for such apertures and adjustable bearing supports for the brush mounted on said closures, the bearing supports being immovable when the closures are in the aperture closing position, said closure provided with inlets adapted to admit clean air about the brush bearings to prevent them from fouling. 100
9. In a suction cleaner a hood provided with a suction nozzle and an end opening for the removal of the brush, a closure therefor, a brush support, a brush mounted in the hood on the support and a connection means between the brush support and the closure, said means comprising interlocking but separable parts said brush support shaped to overhang the end of the brush, but out of contact therewith so as to form a thread guard, said support provided with perforations to permit the passage of air therethrough and about the end of the brush bearing. 105
10. In a suction cleaner a hood provided with a suction nozzle and an end opening for the removal of the brush, a closure therefor, a brush support, a brush mounted in the hood on the support and a connection means between the brush support and the closure, said means comprising interlocking but separable parts said closure, brush support and connection constituting a brush adjusting device, said brush support shaped to overhang the end of the brush, but out of contact therewith so as to form a thread guard, said support provided with perforations to permit the passage of air therethrough and about the end of the brush bearing. 110
11. In a suction cleaner an open suction nozzle a brush mounted for rotation therein, the nozzle being permanently open for the inward passage of air and dirt, one end wall of the nozzle being apertured, a removable end closure for such aperture, an adjustable bearing support for the brush mounted on said closure, the bearing support being immovable when the closure is in the apertured portion. 115
12. In a suction cleaner the combination with a casing provided with a dust inlet, with a brush mounted near such inlet and brush mounting means between the casing and the brush, said casing and brush mount- 120

ing means being provided, one with pins and the other with holes and a bearing protection overhanging, but out of contact with the end of said brush, said protection adapted to 5 permit the passage of air therethrough from said holes and about the end of the brush bearing.

In testimony whereof, I affix my signature in the presence of two witnesses this 6th day of March, 1917.

FRANCIS M. CASE.
